[57] **ABSTRACT**

A movable pressure differential actuated sealing member in the form of a convex-concave rigid shell that has two laterally spaced and aligned arms projecting therefrom that support said shell for pivotal and longitudinal movement relative to the interior face of a rigid spherical sector that is truncated to define an opening therein.

The shell on the surface thereof most adjacent the sector supports a resilient ring. When the opening in the sector and the shell are longitudinally aligned, the ring occupies an encircling position relative to said opening. Upon a substantial pressure differential being established between the interior and exterior of the sector that tends to move the shell towards the sector, the resilient ring is compressed, and the shell acts as a door to seal the opening.

PRESSURE DIFFERENTIAL ACTUATED SEALING MEMBER

BACKGROUND OF THE INVENTION

1. Field of the Invention

A pressure differential actuated sealing member that so operates when disposed in a predetermined position, and the pressure on a first surface thereof adjusted to be greater than on a second opposite surface thereof.

2. Description of the Prior Art

In certain applications it is highly desirable to have a sealing member or door that is capable of withstanding a maximum intended pressure differential, and one that when subjected to not greater than this pressure forms an effective seal, with the sealing member capable of being quickly opened when the pressures on opposite sides thereof are equalized.

In the past, it has been found that the two first requirements above mentioned militate against the third requirement, in that, when a sealing member is of sufficient strength to withstand a substantial differential in pressure, it is usually massive and difficult to move, and requires locks or other sealing devices that are time-consuming to release or fasten.

The present invention is a relatively lightweight sealing member that is capable of withstanding a substantial differential in pressure, is self-sealing, and is considered to overcome numerous operational disadvantages that are inherent to prior art devices of this nature.

SUMMARY OF THE INVENTION

A convex-concave sealing member or door that has two laterally spaced arms projecting therefrom that support said door for pivotal and longitudinal movement relative to a spherical sector that is truncated to provide an opening therein. A resilient opening encircling ring is provided that is interposed between the shell and sector when the shell is longitudinally aligned with the opening. By establishing a substantial differential in pressure between the interior and exterior of the sector, the shell is forced towards the sector to compress the resilient ring and effect a seal therewith, and the seal continuing so long as said differential in pressure is maintained.

A major object of the present invention is to provide a movable convex-concave shell that may be operatively associated with a spherical rigid sector that is truncated to define an opening therein, with the shell when longitudinally aligned with the opening also being in a position to compress a resilient opening encircling ring to effect a seal therewith so long as a differential in pressure is maintained between the interior and exterior of the sector that tends to move said shell towards said sector.

Another object of the invention is to supply a relatively lightweight movable sealing member of extremely simple mechanical structure, one that is compact, is easily operated, and when subjected to a differential in pressure on opposite sides thereof forms an effective seal, and a sealing member that is quick opening after the pressures on opposite sides thereof are equalized.

A still further object of the invention is to supply a sealing member that is held in a sealing position by the differential in pressure on opposite sides thereof, and without recourse to locks or other sealing devices that are time-consuming to release or fasten in locked positions.

Yet another object of the invention is to furnish a movable sealing member that is particularly adapted for space vehicles and marine vessels where compactness of the member, lightness in weight, and efficiency in operation are of paramount importance.

BRIEF DESCRIPTION OF THE DRAWINGS

FIG. 1 is a perspective view of a vessel that has a first form of longitudinally and pivotally movable sealing member that acts as a door to seal an access opening therein;

FIG. 2 is a fragmentary longitudinal cross sectional view of the vessel shown in FIG. 1 taken on the line 2-2 thereof;

FIG. 3 is the same cross sectional view shown in FIG. 2 but with the sealing member in an upwardly extending position;

FIG. 4 is a fragmentary longitudinal cross sectional view of the vessel shown in FIG. 2 and taken on the line 4-4 thereof;

5 FIG. 5 is a fragmentary longitudinal cross sectional view of a vacuum vessel in which a second form of sealing member is mounted on the exterior thereof;

10 FIG. 6 is a perspective view of one of the sealing member supports used with the first form of the device;

15 FIG. 7 is a perspective view of one of the sealing member supports used with the second form of the device;

FIG. 8 is a longitudinal cross sectional view of two spaced pressure vessels provided with movable sealing member that are connected by a pressure equalizing passage, and the piping and valves used for such equalization to permit personnel and material to be transferred from one vessel to the other thereof;

20 FIG. 9 is a fragmentary longitudinal cross sectional view of a pressure vessel provided with a third form of sealing member;

25 FIG. 10 is an enlarged side elevational view of one of the mounting used with the third form of sealing member;

FIG. 11 is a fragmentary longitudinal cross sectional view of a pressure vessel provided with a fourth form of sealing member;

30 FIG. 12 is an enlarged perspective view of a portion of the fourth form of sealing member;

FIG. 13 is a fragmentary longitudinal cross sectional view of a vacuum tank provided with a fifth form of sealing member; and

35 FIG. 14 is a fragmentary perspective view of a large pressure vessel that has a forwardly extending portion of substantially smaller diameter in which an access opening is formed that may be closed by one of the sealing members adapted for this purpose.

DESCRIPTION OF THE PREFERRED EMBODIMENTS

A first form A of the pressure differential actuated sealing member or door assembly is shown in FIGS. 1 to 4 inclusive and FIG. 6 incorporated into a pressure vessel B. The pressure vessel B is illustrated in FIG. 1 as a recompression chamber.

40 Although the first form A of the sealing member is illustrated in conjunction with an individual vessel B, the sealing member is adapted for use with any hollow structure that is subjected to an internal pressure such as a portion of an airborne vehicle or an undersea vessel or the like. In other words, when the word "vessel" is used herein it is to be construed in a broad sense to include any hollow pressure holding structure.

Vessel B is illustrated in FIGS. 1 to 4 inclusive as including 50 an elongate rearward portion 10 that by a first flange 12 is connected by bolts 14 to a second flange 16. Flange 16 has a rigid wall structure C projecting forwardly therefrom that includes a spherical sector 18 that is truncated on the forward portion thereof to define an opening 20 therein. Sector 18 on the interior thereof rotatably supports two axially aligned, laterally spaced stub shafts 22 of transverse circular cross section. The stub shafts 22 are rotatably in sealed journals 24 of conventional design that are secured to the sector 18. It is desirable that at least one of the stub shafts 22 be of sufficient length as to project outwardly through its supporting journal, with the outwardly projecting portion having a handle 26 or other means (not shown) for pivoting the shaft in engagement therewith.

55 60 Stub shafts 22 on their inner ends develop into extensions 22a that are of generally rectangular transverse cross section for reasons that will later be explained. A dimensionally stable sealing member D formed from either a metallic or non-metallic material is provided that is in the form of a circular convex-concave shell that has two laterally spaced arms 28 projecting rearwardly therefrom. Sealing member D is disposed inside wall structure C. The sealing member D has a diameter greater than the diameter of opening 20.

65 70 Stub shafts 22 on their inner ends develop into extensions 22a that are of generally rectangular transverse cross section for reasons that will later be explained. A dimensionally stable sealing member D formed from either a metallic or non-metallic material is provided that is in the form of a circular convex-concave shell that has two laterally spaced arms 28 projecting rearwardly therefrom. Sealing member D is disposed inside wall structure C. The sealing member D has a diameter greater than the diameter of opening 20.

75 80 Sealing member D has a convex forward surface 30 that is substantially the same as the interior surface 32 of wall struc-

ture C. Arms 28 curve longitudinally as may best be seen in FIG. 4, and each has a radius of curvature slightly less than that of said interior surface 32 from which each arm is spaced a small distance. The arms 28 on the rearward portions thereof have elongate slots 34 defined therein, which slots are slidably engaged by extensions 22a.

Surface 30 of sealing member D supports a ring 36 of resilient elastomeric material such as rubber or the like. The internal diameter of ring 36 is at least as great as the diameter of opening 20. Ring 36 is preferably mounted on a circular recess 38 that extends inwardly from surface 30 of sealing member D. The ring 36 is of sufficient thickness as to project forwardly from recess 38, with the forward face of the ring curving radially at substantially the same radius of curvature as the interior concave surface 32 of wall structure C.

Sealing member D preferably has a centrally disposed recess 42 formed therein that extends rearwardly from the forward surface to the sealing member D that extends across the recess. The bar 44 serves as a second handle that may be used to manipulate sealing member D relative to vessel B.

When it is desired to seal the opening 20, the sealing member D is pivoted to a position where it is longitudinally aligned with the opening 20. The handle 44 may be used to move the sealing member D forwardly relative to wall structure C to place ring 36 in light pressure contact with inner surface 40. The pressure inside wall structure C is increased by means (not shown) to be above that on the exterior of the vessel, with the differential in pressure compressing the ring 36 to effect a fluid tight seal about opening 20. It will be apparent from the above description that the slots 34 must be of sufficient length as to permit a substantial forward longitudinal movement of sealing member D to wall structure C to effect sealing of opening 20.

Wall structure C preferably has a first stop 46 on the interior thereof that is engaged by sealing member D when the sealing member is longitudinally aligned with opening 20. A second stop 48 is provided in the pressure vessel B to support the sealing member D in the upright position illustrated in FIG. 3. If the pressure inside vessel B is increased suddenly when the sealing member D is longitudinally aligned with opening 20, the differential in pressure on sealing member D alone will be sufficient to move the sealing member longitudinally for ring 36 to pressure contact surface 32 and effect a seal therewith.

A second form E of the sealing member assembly is shown in FIG. 5 and is adapted for use on a vessel B in which a negative pressure is maintained relative to that of the ambient atmosphere. The sealing member 50 in the second form E of the device is a segment of a spherical shell that is of sufficient width to extend across the opening 20 in the spherical wall sector 18 that forms a part of the vessel B. The sealing member 50 has two short stub shafts 52 that are axially aligned and laterally spaced from one another as shown in FIG. 5. The stub shafts 52 are pivotally and rotatably supported in two elongate slots 54 as may best be seen in FIG. 5.

The sealing member 50 on the interior face 56 thereof supports a flat resilient ring 58 of sufficient diameter as to extend around a portion of the spherical sector 18 adjacent opening 20. The resilient ring 58 is preferably mounted in a recess 60 defined on the inner surface of the sealing member 50, but with the ring of sufficient thickness to project outwardly from the recess.

When it is desired to use the second form E of the sealing member assembly, the sealing member 50 is longitudinally aligned with the opening 20, and a slight pressure asserted on the sealing member to force the ring 58 into pressure contact with the exterior surface of the spherical sector 18. The interior of the vessel B is now partially evacuated to cause a negative pressure to exist therein with the differential in pressure between the interior of the vessel and the pressure of the ambient atmosphere forcing the ring 58 into sealing engagement with the sector 18, and this sealing engagement continuing so long as a differential in pressure is maintained between the in-

terior and exterior of the vessel B. Upon it being desired to move the sealing member 50 to a position where it does not obstruct and seal the opening 20, the pressure between the interior and exterior of the vessel B is equalized by means (not shown), which allows the sealing member 50 to be pivoted to a position where free access may be had to the interior of the vessel B through the opening 20. Details of the stub shafts 52 and the slots 54 that are rotatably and slidably engaged thereby are shown in FIG. 7.

In FIG. 8 two of the vessels B are shown in axially aligned and longitudinally spaced relationship, that have the openings 20 therein adjacently disposed and connected by a passageway defining structure F. The two vessels are each provided with first form A of the sealing member assemblies as

described in detail in conjunction with the first form of the invention shown in FIGS. 1 to 4 inclusive and FIG. 6. First, second, third, fourth, and fifth valves 62, 64, 66, 68 and 70 respectively are provided. Valves 62 and 70 are connected by conduits 62a and 70a to the interiors of the vessels B. Valves 64 and 68 are connected by conduits 64a and 68a to the interior of the passageway defining structure F. Conduits 72 connect the valves 62 and 64 to valve 66, and the valve 66 is also connected by conduits 74 to the valves 68 and 70.

When both vessels B are pressurized and the first form of sealing member assemblies A are in the sealing position shown in FIG. 8, materials or personnel can be transferred from one vessel to the other by the following procedure. Assuming that the material to be transferred is in the vessel B on the right hand side of the FIG. 8, valves 68 and 70 are opened, while valves 62, 64 and 66 remain in the closed positions. Pressure on the interior of the vessel B on the right hand side of FIG. 8 is now equalized with that existing within the confines of the passage defining structure F.

Valves 62 and 64 are now opened to permit pressure in the vessel B on the left hand side of FIG. 8 to equalize with that existing in the passageway defining structure F. The pressure in the passageway defining member F is now equal to that existing in the two pressure vessels B, and the first sealing member assemblies A may be disposed in the open position to permit transfer of material or personnel from one vessel B to the other. Pressure in the two vessels B may be equalized by opening valves 62, 66 and 70 while valves 64 and 68 are closed, and this equalization taking place without in any way effecting the pressure within the passageway defining structure F. Actuation of the first forms A of the sealing member assemblies on the dual vessels shown in FIG. 8 is preferably by use of handles 26 as described previously in conjunction with the form of the invention shown in FIGS. 1 through 4 inclusive.

A third form of sealing assembly G is shown in FIG. 9 in conjunction with a pressure vessel B and differs from the first form in that the resilient sealing ring 36 is secured to the interior surface 32 of the spherical sector 18. The third form of sealing assembly G has a circular convex-concave sealing member 71 of the same configuration as used in the first form A, but without recesses 38 being formed therein. Two non-rotatable stub shafts 72 extend towards one another from the interior surface of the spherical sector 18, are axially aligned, and laterally spaced from one another. The stub shafts 72 have truncated portions 74 as best seen in detail in FIG. 10. The shafts 72 are rotatably engaged by openings 76 formed in arms 28 of the third form of sealing member G and these openings 76 being in communication with longitudinally extending slots 78 also formed in the arms. When the third form of sealing member assembly G is longitudinally aligned with the opening 20, the sealing member 71 can be moved forwardly for the forward face thereof to engage the resilient ring 36, due to the slots 78 now being aligned to engage the truncated portions of the shaft 72. The third form G of the sealing assembly operates in the same manner and accomplishes the same result as the first form A thereof.

A fourth form H of the invention is shown in FIGS. 11 and 12 that is identical with the first form A, other than that no

resilient ring 36 is used. The spherical sector 18 has a raised ground face 73 that is adapted to be engaged by a complimentary raised face 72 formed on the forward peripheral portion of the fourth convex-concave sealing member 77. The faces 73 and 75 are ground sufficiently accurately that a fluid tight seal is provided when they are in pressure contact with one another.

A fifth form J of a sealing assembly is shown in FIG. 13, that is adapted for use with a vacuum vessel K that has a downwardly and inwardly extending circular flange 74 that defines an opening 78. Two laterally spaced webs 80 project forwardly from vessel K that rotatably support two laterally spaced stub shafts (not shown) that have extensions 22a'. The extensions 22a' engage elongate slots 82 that are formed in laterally spaced arms 84 secured to a convex-concave sealing member 85. The fifth form of sealing member assembly J has a resilient ring 86 mounted on sealing member 85, which ring may sealingly contact the forward face of the circular flange 76 when the pressure on the interior of the vessel K is less than that on the exterior thereof. The differential in pressure will maintain the fifth form of sealing member assembly J in a sealing position on the vessel K so long as this differential prevails.

FIG. 14 illustrates a large vessel L in which a substantially smaller spherical sector 18 projects therefrom, and an opening 20 in the sector capable of being closed by use of a first form A of the sealing assembly such as described in connection with the first form of the invention shown in FIGS. 1 to 4.

I claim:

1. In combination with a rigid wall sector that has an interior surface that can be subjected to a pressure greater than the pressure on the exterior of said sector, at least a portion of said interior surface being of arcuate shape and extending around a circular opening in said wall sector, a movable sealing member assembly which when in a first position permits unobstructed passage through said circular opening and when in a second position is centered relative to said opening and cooperating with said sector to seal said opening, said sealing member assembly including:

- a. a resilient circular ring having an internal diameter greater than the diameter of said opening; 40
- b. a rigid circular plate of greater diameter than said opening, said plate having a first surface on which said resilient ring is mounted, with at least the portion of said first surface within said ring being of convex shape and having a radius of curvature that is substantially the same as that of said interior surface of said wall sector, said plate being situated within the confines of said wall sector, said convex first surface of said plate when said assembly is in said first position being adjacently disposed to the interior surface of said sector, and when said assembly is in said second position being centered relative to said opening for sealing the same; 45
- c. a pair of opposed transverse shafts rotatably and sealingly supported in the opposed side walls of said sector, with at least one of said shafts having a portion extending outwardly of said sector, the end of the said one shaft disposed within the sector being generally rectangular in cross section; 50

60

d. a pair of arms rigidly connected to said plate and extending therefrom into the interior of said sector, said arms being received on said shafts, said arms being formed with elongated slots the width of which generally correspond dimensionally to the rectangular end portion of said shaft, and

e. a handle at the exterior side of said sector secured to said outwardly extending portion of said one shaft for rotating the same and thus said plate, said plate, upon rotation of said handle, is moved from said first, unobstructed position to said second position centered relative to said opening to permit tight sealing of said opening by said sealing ring when the interior of said sector is pressurized.

2. In combination with a rigid wall sector that has an interior surface that can be subjected to a pressure greater than the pressure on the exterior of said sector, at least a portion of said interior surface being of arcuate shape and extending around a circular opening in said wall sector, a movable sealing member assembly which when in a first position permits unobstructed passage through said circular opening and when in a second position is centered relative to said opening and cooperating with said sector to seal said opening, said sealing member assembly including:

- a. a resilient circular ring having an internal diameter greater than the diameter of said opening;
- b. a rigid circular plate of greater diameter than said opening, said plate having a first surface on which said resilient ring is mounted, with at least the portion of said first surface within said ring being of convex shape and having a radius of curvature that is substantially the same as that of said interior surface of said wall sector, said plate being situated within the confines of said wall sector, said convex first surface of said plate when said assembly is in said first position being adjacently disposed to the interior surface of said sector, and when said assembly is in said second position being centered relative to said opening for sealing the same;
- c. a pair of opposed transverse shafts rotatably and sealingly supported in opposed sidewalls of said sector, with at least one of said shafts having a portion extending outwardly of said sector;
- d. a pair of laterally spaced arms situated in said sector and having first and second ends, said first ends of said arms being rigidly secured to opposite peripheral portions of said plate;
- e. a handle secured to said portion of said one shaft that extends outwardly from said sector; and
- f. means including an elongate slot on the second end of at least one of said arms for operatively connecting said second end to said one shaft so that said plate by manipulation of said handle may be selectively rotated to either said first or second positions, with said means permitting both pivotal and longitudinal movement of said plate relative to said sector, said longitudinal movement when said plate is centered with said opening in said sector permitting said resilient ring to effect pressure sealing contact with a predetermined interior surface section of said sector upon pressurization of the interior of said sector.
